UNITED STATES PATENT OFFICE.

SIMON W. WARDWELL, OF PROVIDENCE, RHODE ISLAND.

COP OR PACKAGE OF YARN FOR DYEING.

SPECIFICATION forming part of Letters Patent No. 712,986, dated November 4, 1902.

Application filed November 20, 1901. Serial No. 83,036. (No model.)

To all whom it may concern:

Be it known that I, SIMON W. WARDWELL, a citizen of the United States, residing at Providence, in the county of Providence and 5 State of Rhode Island, have invented certain new and useful Improvements in Cops or Packages of Yarn for Dyeing, of which the following is a specification.

My invention relates to improvements in 10 winding, supporting, and retaining yarn or like material in porous cops or packages in which such material can be effectively subjected to dyeing, mordanting, bleaching, steaming, scouring, washing, or kindred processes.

The object of my invention is to provide a cop or package whereby the yarn may be wound into the form of a cone or cylindrical tube of uniform porosity and in such manner 20 as to be retained in its original conformation to be submitted to dyeing and similar processes above referred to and from which the yarn can be subsequently unwound by drawing same over the end of the package to insure maximum speed of delivery and uniformity of tension.

The accompanying drawings disclose the details of my invention, representing, respectively, Figure 1, a side view in part section, 30 showing the relation of the cop to the tube in winding; Fig. 2, a side view showing the cop prepared for removal from the mandrel of the winding-machine and ready for subjection to the finishing process; Fig. 3, a side view showing another means for fastening the tube to retain the yarn in dyeing; Fig. 4, a side view showing the tube in somewhat different form; Fig. 5, the cop and tube mounted in position for delivering the yarn after finishing.

40 In Fig. 1 I have shown a cop wound upon a conical mandrel or tube-holder, producing a yarn mass in the form of a truncated cone, such a form facilitating the delivery of the yarn over the end in unwinding. The cop is preferably of an outside diameter not much greater than the internal diameter—that is, the cop is wound upon a larger tube than usual in proportion to the exterior diameter, presenting an increased area of the material 45 to the action of the liquor or gas, and therefore insuring thorough penetration of the body of the cop by the liquor. The pre-

ferred system of winding by which the cop is produced is that known to those versed in the art as the "universal" or V wind. I have 55 proved by investigation and experiment that by employing this system of winding in conjunction with suitable holders or tubes, as hereinafter described, a cop may be produced which will readily and uniformly bleach, dye, 60 &c., and after treatment will deliver by unwinding over the end with greater uniformity of tension, less breakage, and at higher speed than any other package after such dyeing, &c. As described in my reissued Letters Patent 65 No. 11,856, dated September 18, 1900, the method of winding consists generally in laying the yarn on the cop tube or support in successive layers of crossed helices, each portion of the yarn between the ends of the cop being 70 so laid around the tube that when reversed and carried in like manner to the opposite end it will cross and tie down the portion first laid at one or more points. The cop is built up of such portions or helices of yarn, 75 all alike in the number of turns in each, and their intersections, with reverse portions. Each helix in each layer lies throughout its length parallel to and close beside the yarn of a previously-laid helix, and at each end of the 80 cop the yarn is carried back abruptly, forming a sharp bend or knuckle when the yarn crosses over the bend of a previous helix at that end. The bend of the yarn of each helix at each end of the cop is so disposed on the 85 periphery of the cop relative to the bend of the helix previously laid at the same end that each helix lies adjacent a previously-laid helix running in the same direction. Heretofore this system of winding has been employed 90 with the purpose generally of producing cops which while possessing uniform tension of delivery shall be exceedingly compact to economize space in packing or to insure a maximum amount of material in the bobbin or 95 holder in which it is employed in the machine. To this end the yarn has been so wound that each helix lies closely adjacent to its neighbor.

In carrying out my improvement I "open" the wind, causing the helices to lie apart 100 slightly to produce a cop of uniformity of texture and of substantially uniform porosity, and although the innermost coils and layers may be somewhat compressed by the elastic

constriction of the outer coils of the cop this is remedied by permitting these inner layers to collapse, as will be hereinafter described. The method of winding described secures in the cop a maximum amount of material so disposed as to produce a cop of maximum porosity and is therefore preferable; but other methods of winding may be employed.

The cop-tube, which supports the package after removal from the winding-spindle, may be formed of any flexible or elastic material. A substantially reticulated fabric is preferable, with meshes sufficiently large to permit a free penetration and circulation of the liquor or gas. It may be woven, knit, or otherwise fabricated to conform to the shape of the mandrel of the winding-machine or shaped thereto from a sheet of material sewed or fastened in cylindrical or conical form.

Referring first to Fig. 1, B shows a mandrel of a winding-machine of greater diameter than usual, and a flexible tube or sleeve A is drawn over the mandrel, forming a close-fitting adhesive covering therefor and having extending ends *a a*, which are disposed in any convenient manner to be out of the way in winding. As shown, the mandrel has a pocket or groove *b*, and the inner end of the tube is tucked into the pocket. The outer end may lie loosely on the nose *b'* of the mandrel. After the cop A has been wound to its predetermined thickness in the manner prescribed or otherwise the ends or extinctions *a a* of the tube A are rolled or folded back over the yarn mass, as shown in Fig. 2. The smaller end may be lapped over the larger to retain them in position, or the ends may be connected by a lacing-cord *x*, (shown in Fig. 3;) but in most instances the adhesion of the fabric to the yarn is sufficient to keep the ends in place. Another construction of the tube B is shown in Fig. 4, in which the ends are formed into tongues *c* and are laced together. Other methods might also be employed, the salient feature being the retention of the coils in their proper relation on the cop by extensions of the cop-tube of the character specified folded back over the ends of the cop. Thus protected the package may be removed from the winding-spindle without damage to its ends and can then be introduced directly to the bath or subjected to the gas, as required in the desired treatment. The liquor or gas easily circulates through the tube A and through the comparatively thin walls of the tubular mass of yarn, and any shrinkage of the yarn occurring simply contracts the tube A without binding the layers of yarn thereon or materially compacting the package. It is not required that the cops retain absolutely their cylindrical or conical form for and during their subjection to the permeating fluid. Therefore stiffening or sizing of the tube is unnecessary, and I have fully determined by experiment that after the extensions *a a* have been folded over the ends of the cop the latter may be flattened out and subjected to

considerable rough handling without disarrangement of the coils or injury to the yarn. After the yarn has been finished and dried the tube A may be placed on a mandrel or other suitable support, with the ends or extensions *a a* so disposed as to be out of the way in unwinding. As shown in Fig. 5, the smaller end is tucked into the end of the hollow support C and the larger end is allowed to hang down loosely over the base of the support. The yarn is now free to be delivered by unwinding over the end to any appropriate machine in any process.

The advantages of a dye-cop wound in the above-described manner are the following: The yarn is massed in compact form, and hence the cop is most convenient for handling, packing, and shipping. The coils of yarn crossing and recrossing each other regularly between the ends of the package form each layer in a kind of network, and the combination of these layers forms a package with myriad pores substantially uniform in size and relation, through which the dye fluid may penetrate freely and uniformly. The regular crossing of the yarns imparts stability to the package, and the abrupt reversal of each coil at the end of the package prevents the coils from falling over the end in handling or from other causes. The most important advantage lies in the fact that the yarn can be unwound from the cop over the end at high speed, thus economizing floor-space and labor and minimizing waste of yarn. Heretofore the only practical method of dyeing and similarly treating yarns has been to treat it in skeins. This method involves several distinct winding operations, all of which are slow and costly. Prior to dyeing the yarn must be reeled into skein form. Before the skeins are removed from the reels leases must be tied in at various points to maintain the yarn in position in the skein and secure and locate the leading end. In the process of dyeing the yarn becomes more or less tangled between the leases, which are so few in number and so far separated as to be inadequate to prevent entanglement of the yarns. In some processes the yarn is wound directly from the skein to the quill or bobbin which is to be employed in subsequent operations. This operation is a particularly slow one. Before the skeins can be unwound they must be straightened and the yarns freed, performed by throwing one end of the skein over a pole or hook and pulling or jerking the other end sharply while shifting the skein about its support. The skein is then placed upon the swift (a form of reel employed to support the skein during the unwinding) and again straightened in place, the leases cut, and the leading ends secured. The winding can be done only at very low speed, for no matter how delicately hung and well-balanced the swift its mass is so great that it cannot be started to rotate quickly and suddenly. The inertia of the swift and its yarn so resists the

pull of a sudden start as to cause the yarn to break when a fine yarn or a loosely-twisted material is being wound. So great are the difficulties of winding fine yarns from the 5 skein that manufacturers have dyed the raw material before carding and spinning, thus obtaining their fine colored yarns direct from the spinning machinery. The disadvantages of this method are obvious. Besides the additional expense attending this method of handling the exact character of the yarn and the purpose for which it is to be used must be determined prior to its manufacture. Where yarn can be dyed in the skein or in 15 equivalent form no attention need be paid in spinning to the ultimate purpose for which the yarn is intended, so far, at least, as color is concerned. A large quantity of yarn can be carried continuously through the spinning 20 operations and after completion can be parceled out for various purposes and treatments as desired. When dyed in the fleece or raw state, the various machines through which the dyed material is passed must be 25 most carefully cleaned before a new color can be spun. The swifts from which the yarn is unrolled are seldom balanced. The yarn is not supported equidistantly from the axis of rotation, so that the swift receives intermittently an impetus to a faster rotation than its normal speed. This impetus comes from and with a sudden pull on the yarn, or, what is the same thing, with increased tension. With accelerated motion due to the pull and 35 carried by its own momentum the swift runs ahead for a time, delivering the yarn with excessive freedom, gradually slackening its speed until a fresh impetus is received. In this way the tension of delivery fluctuates, tending to 40 a corresponding irregularity in the fabric in which the yarn is ultimately incorporated. In some instances it is found necessary to wind the yarn from skeins in single end to spools and thence rewind it to jack-spools with a plurality of ends and again to wind from the jack-spools to the quill or other package. By unwinding over the end of the package the effects of momentum and inertia are entirely 45 eliminated, and hence the irregularity of tension and liability to breakage are decreased and the speed at which the yarn can be delivered is greatly increased. By winding at higher speed over the end of package and directly from the package in which the yarn 55 is dyed an economy is effected in the cost of winding by reducing the number of machines required and the number of operators heretofore necessary to operate them and in the floor-space occupied by the winding and 60 other attendant machinery. The product per operator in winding is increased, because less time is expended in keeping the winding-machines supplied with yarn. The dye-cop contains more yarn than does a skein, and 65 hence the winding-supply does not need to be replenished so frequently. When the supply must be replenished, it is only necessary

to place a new cop on the supply-holder, tie up the ends, and start the winding. All the yarn will be withdrawn from the supply-package without requiring further attention on the part of the operator. When a skein-supply is employed, the supply must be frequently replenished, time is consumed in straightening the skein and preparing it for 70 unwinding, as above indicated, and in piecing broken ends and freeing snarls and tangles after the winding has been started. Further, the yarn may be directly employed in some instances in the production of fabric—as, for 75 instance, in manufacturing knit goods. The most effective way of preparing yarn for use in knitting-machines at the present time is to spool it from the skeins and then wind it from the spools into cones. Where my improved 80 package can be employed, the two operations of spooling and coning are eliminated.

Attempts have been made to dye yarn in the cop; but they have not been successful, because, first, appropriate tubes were not 85 perfected on which to wind yarns prior to dyeing, and, second, the method of winding and supporting the cop employed was not such as to insure in the cop a uniform porosity or absorbent capacity. Tubes or supports of many 90 materials have been proposed, but principally wire-cloth or perforated metal. Such tubes because of their rigidity cause a variation in the density and porosity of the cop, as the outer layers of the latter constrict the inner 95 ones, compressing them and rendering the 100 interior portion of the cop adjacent the tube more dense. A flexible tube of appropriate material yields readily under the constrictive pressure, permitting the interior portion of 105 the cop to collapse, thereby tending to loosen its inner coils and equalize its porosity. In the methods of winding dye-cops heretofore employed no attempt has been made to lay the yarns regularly and precisely. Consequently the coils contact in some places, limiting absorption, and in others, being widely separated, provide for quicker permeation, and therefore the material is unevenly treated and an uneven product results. Again, 115 if the coils of one layer are laid parallel, or nearly so, to those of an adjoining layer the coils of one layer in shrinking will be forced between those of the underneath layer. In unwinding this will cause extra and uneven 120 tension on the yarn. The crossing of the coils in the successive layers in the universal method of winding hereinbefore described prevents their being pulled into the 125 yarn mass to hinder free delivery, while their peculiar and systematic disposition aids the drawing off of the yarn and preserves the original conformation of the cop.

Without limiting myself to the use of tubes of any special form or material, I claim as 130 my invention—

1. A yarn package for dyeing, &c., consisting of a flexible hollow cop and a holder of open fabric extending through, across the

ends and over the outside of the cop, substantially as set forth.

2. A yarn package for dyeing, &c., consisting of a flexible hollow cop, in which the 5 yarn is laid in separated superposed coils as set forth, and a holder of open fabric extending through, across the ends and over the outside of the cop, substantially as described.

3. A yarn package for dyeing, &c., consisting of a flexible hollow yarn package, and 10 a holder of open fabric extending through,

across the ends and over the outside of the cop, with its ends secured together, substantially as set forth.

In testimony whereof I have signed my 15 name to this specification in the presence of two subscribing witnesses.

SIMON W. WARDWELL.
